COMBINED TYPEWRITER STAND AND DESK

George H. Hamilton, East Grand Rapids, Mich.,
assignor to American Seating Company, Grand
Rapids, Mich., a corporation of New Jersey

Application March 19, 1931. Serial No. 523,717

1 Claim. (Cl. 45—91)

The present invention relates to desks and more particularly to typewriter desks designed for use by typists and stenographers.

The main objects of the invention are to 5 provide a typewriter stand having a top which serves as a combined desk and cover which may be lifted and swung rearwardly when the typewriter is being used; to provide such a structure whose top provides a desk when the typewriter 10 is not in use; and to provide a structure of the character above specified which is neat in appearance, highly utilitarian in use, and economical to produce.

An illustrative embodiment of the invention 15 is shown in the accompanying drawing, wherein:

Figure 1 is a perspective view of the desk and its attached chair, showing the top swung rearwardly, the dotted lines indicating the position to which the top may be lowered and retained 20 when the typewriter is being used;

Figure 2 is a fragmentary sectional view showing in dotted lines the position assumed by the top in its initial tilting movement and thereafter in its retained lower position:

Figure 3 is a fragmentary view partly in section, showing the top in its retained position; showing the top in its retained lower position; and

Figure 4 is a fragmentary view of the slot 30 in which the pivot pin travels and is retained.

Referring to the drawing in which like numerals designate the same parts in the several views, the combined stand and desk is adjustably supported for height by the vertically disposed tubular member 1 which telescopes with the tubular member 2. A clamp 3 is provided for adjusting the height of the combined stand and desk and a U-shaped member 4 having laterally projecting oppositely disposed legs 5 at its opposite ends is spot welded or otherwise suitably secured to the tubular member 2 at one end and to the tubular member 6 at its other end. The tubular member 6 adjustably telescopes with the tubular member 7 and the 45 clamp 8 is provided for adjusting the height of the chair 9 which is provided with a back 10.

A horizontally disposed stand 11 for supporting a typewriter, not shown, is provided with a back 12 and a pair of rearwardly disposed 50 laterally projecting pivot pins 13. A cover 14 for the stand has an inclined desk portion 15, depending front portion 16 and depending side portions 17 which form a closure for the typewriter supporting stand when the desk cover is 55 in its closed position. Oppositely disposed

blocks 18 secured to the inner lower front end of the side portions 17 are adapted to rest on the upper side of the stand 11 for supporting the forward end of the desk cover 14 when the typewriter is not being used.

Suitably secured to the side members 11 to their respective inner surfaces is a pair of plates 19 having L-shaped slots 20. The pivot pins 13 register with these slots and are retained and are adapted to travel therein.

In actual use, the top 14 forms a combined cover for the typewriter and a desk. This top is hingedly mounted by means of the pivot pins 13 which are retained and are adapted to travel in the slots 20. The top may be tilted rearwardly until it assumes a vertical position as shown in full lines in Figure 1 at which time it may be slid forwardly and permitted to drop to the retained position shown in dotted lines in Figure 1. In this position the typewriter may 75 be used while, when the top is returned to the position shown in full lines in Figure 2, the top may be used as a desk.

It will thus be seen that a combined desk and typewriter stand is herein shown and described 80 in which the desk portion serves as a cover for the stand when the typewriter is not in use yet which can be readily tilted rearwardly when it is desired to use the typewriter.

While but one specific embodiment of this 85 invention has been herein shown and described, it will be understood that numerous details of the construction shown may be altered or omitted without departing from the spirit of this invention as defined by the following claim. 90

I claim:

The combination with a horizontally disposed stand having an upwardly extending portion forming a back, said stand provided with a pair of rearwardly disposed laterally projecting pins, of a desk having depending side and front portions forming a cover for said stand, said desk having a pair of linear oppositely disposed slots registering with said pins and in which the pins are adapted to travel whereby the desk is 100 tilted rearwardly and dropped to retained open position.

GEORGE H. HAMILTON.
